UNITED STATES PATENT OFFICE.

MARION W. PITNER, OF CHICAGO, ILLINOIS.

DESIGN FOR A LIGHTING-FIXTURE.

No. 40,215.

Specification for Design.

Patented Aug. 10, 1909.

Application filed May 24, 1909. Serial No. 498,105. Term of patent 14 years.

To all whom it may concern:

Be it known that I, MARION W. PITNER, a citizen of the United States, residing in Chicago, in the county of Cook and State of Illinois, have invented a new, original, and ornamental Design for Lighting-Fixtures, of which the following is a specification, reference being had to the accompanying drawing, forming a part thereof.

The figure is a perspective of a lighting fixture showing my design.

I claim—

The ornamental design for a lighting fixture as shown.

MARION W. PITNER.
